UNITED STATES PATENT OFFICE.

DAVID ROSS BERRY, OF ROCKAWAY, NEW JERSEY.

AIR-VALVE.

SPECIFICATION forming part of Letters Patent No. 517,184, dated March 27, 1894.

Application filed June 21, 1893. Serial No. 478,327. (No model.)

To all whom it may concern:

Be it known that I, DAVID ROSS BERRY, a citizen of the United States, residing at Rockaway, in the county of Morris and State of New Jersey, have invented certain new and useful Improvements in Air-Valves, of which the following is a specification.

This invention relates to air valves adapted for use on vessels or chambers holding air under pressure, and which through the medium of the valve may be detachably connected to the source of air supply, when said vessel or chamber is being charged. The valve device hereinafter described is particularly adapted to be used in connection with pneumatic tires of bicycles.

In the drawings, Figure 1 is a sectional elevation of my improved valve device shown applied to the pneumatic tire of a bicycle. Fig. 2 is a sectional view of the valve and its case, detached. Fig. 3 shows the split clamping sleeve, and Figs. 4 and 5 are a plan and elevation, respectively, of the valve follower.

The valve case *a* has its bore *a'*, valve seat *a²* and chamber *a³* on a common axis. The interior of the chamber *a³* is screw threaded and in this chamber is snugly fitted the corresponding screw threaded follower *b*, the upper end of which is provided with a knurled head *b'*, by means of which it is manipulated. This follower has a central bore and a valve seat *b²*, the lower part of the bore below the valve seat being enlarged to receive, and act as a guide for, plug *c*. This plug *c* has a valve formed on its two ends and is of such a length that the upper valve is seated firmly in the valve seat of the follower *b* and the lower valve seated firmly in the valve seat of the case *a* when the follower *b* is screwed down in the chamber *a³*, as shown at Fig. 1. From the upper end of the plug *c* extends a rod or stem *c'*, which passes through, and is somewhat longer than part of the central bore of the follower *b* above the valve seat *b²*. This stem is provided with a button or flange *c²* a little larger in diameter than the bore of the follower. By this arrangement the plug *c* is suspended with its valves away from the valve seats *a²* and *b²* when the follower *b* is partly unscrewed from the chamber *a³*, as shown at Fig. 2, and this is the arrangement of the parts of the device when the tube or

chamber to which it is attached is being charged or inflated with air, the coupling or connection of the source of air supply then being fitted on the case *a* by its external screw thread.

To provide for the air passing freely through the device, slots *b³* *b³* are formed in the top of the follower *b*, opening into the upper end of the bore, and slots *b⁴* *b⁴* transversely formed through the lower part of the follower, extending therein nearly to the valve seat *b²*. Now upon the removal of the air compressor or the coupling of the source of air supply, the pressure in the tube or chamber, inflated, forces the plug against the seat *b²* thereby preventing escape of air, both valves then being firmly closed by screwing down the follower *b*, as before described. From the sides of the plug *c* project pins *c³* *c³* which extend into the slots *b⁴* *b⁴* of the follower *b*, and so cause the plug to be rotated with the follower.

d is a cap for excluding dirt, &c., from the interior of the device.

The means here adopted for securing air valves to the tires of bicycles or to other flexible connections of other air chambers, consists of the grooved neck or coupling *a⁴* of the valve case *a*, adapted to be inserted in the tubular neck *e* of the elastic tube *e'* the screw threaded sleeve *f* having a smooth bore to fit over the tubular neck *e* and provided with slits *f'* *f'*, and the nut *g* fitted to turn on the screw thread of the sleeve *f*, said screw thread being cut deeper at its upper end or made taper in form, so that the nut *g*, when forced down on the sleeve will contract it and cause it to press the tubular neck *e* tightly against the grooved coupling *a⁴*.

To fasten the elastic tube *e'* to a metal tire *h* of a bicycle, the lower end of the sleeve *f* is formed with a flange *f²*. The sleeve passes through a hole in the tire *h* and said tire is clamped rigidly between the flange *f²* and nut *g*. Or where a covering *i* is used to protect the elastic tube *e'*, the flange *f²* of the sleeve then presses the edges of this covering against the metal tire *h*, when the nut *g* is screwed home, and at the time the tubular neck *e* is clamped between the sleeve *f* and the grooved coupling pipe *a⁴*.

I claim as my invention—

1. The combination of the valve holding device having a grooved coupling neck, adapted to be inserted in a flexible tube, a screw threaded sleeve, and a tightening nut.
- 5 2. The combination of the valve holding device having a grooved coupling neck, adapted to be inserted in a flexible tube, a split taper screw threaded sleeve, and a tightening nut.
3. The combination of the valve holding device having a grooved coupling neck, adapted to be inserted in a flexible tube, a plate or frame through which the flexible tube passes, a flanged screw threaded sleeve, and a tightening nut for securing the flexible tube and the valve holding device to the plate or frame.
- 15 4. The combination of the valve holding device having a grooved coupling neck, adapted to be inserted in a flexible tube, a plate or frame through which the flexible tube passes, a flanged split taper screw threaded sleeve, and a tightening nut for securing the flexible tube and the valve holding device together, and to the plate or frame.
- 20 5. The combination of the valve case having a screw threaded exterior and a central chamber and bore and a valve seat formed therein, a cylindrical plug, having a valve formed on its end, a follower serving as a plug to close said chamber and having a central bore to 25 guide and control the valve plug, and adapted to force and hold the valve against its seat, and a cap screwing upon the exterior thread of the case.
- 30 6. The combination of the valve case, having a central chamber and bore and a valve seat formed therein, a cylindrical plug, having a valve formed on each of its ends, and a follower having a valve seat and a central bore to guide and control the valve plug and adapted to force and hold the valves against their 35 seats.
- 35 7. The combination of the valve case having a central chamber and bore, and a valve seat formed therein, a cylindrical plug, having a valve formed on its end, a follower having a central bore to guide and control the valve plug, and having a button or flange on its upper end.
- 40 8. The combination of the valve case, having a chamber and bore and valve seat formed therein, a screw threaded follower in the chamber of the valve case having a central bore 45 and transverse slots at its lower end, a plug with a valve formed on its end and having guide pins arranged to work in the transverse slots of the follower.
- 50 9. The combination of the valve case, having a chamber and bore and valve seat formed
- therein, a screw threaded follower in the chamber of the valve case, having a central bore, a valve seat, and transverse slots at its lower end, a plug with a valve formed on each of its ends, having guide pins arranged to work in the transverse slots of the follower, and a stem projecting from the valve plug through the follower and having a flange or button on its upper end.
- 55 10. The combination of the valve case, having a chamber and bore and valve seat formed therein, a screw threaded follower in the chamber of the valve case, having a central bore, a valve seat, transverse slots at its lower end, and transverse slots opening into the upper end of the central bore, a plug with a valve formed on each of its ends and having guide pins arranged to work in the lower transverse slots of the follower, a stem projecting from the valve through the follower and having a flange or button on its upper end, and a cap fitting over the valve case.
- 60 11. The combination of the valve case, provided with a grooved coupling neck, and having a chamber and a bore and valve seat formed therein, a screw threaded sleeve, a tightening nut therefor, a screw threaded follower in the chamber of the valve case, having a central bore, a valve seat and transverse slots at its lower end, a plug with a valve formed on each of its ends, and having guide pins arranged to work in the transverse slots of the follower, and a stem projecting from the valve plug through the follower and having a flange or button on its upper end.
- 65 12. The combination of the metal tire of a bicycle, the elastic tube of a pneumatic tire having a projecting air tube, a valve case provided with a grooved coupling neck, a screw threaded sleeve provided with a flange, and a nut between which and the flange of the sleeve the metal tire is clamped.
- 70 13. The combination of the metal tire of a bicycle, the elastic tube of a pneumatic tire having a projecting air tube, a covering for the elastic tube, a valve case provided with a grooved coupling neck, a split taper screw threaded sleeve provided with a flange, a nut between which and the flange of the sleeve the covering and the metal tire is clamped, at the same time the split sleeve is forced against the air tube on the coupling neck of the valve case.
